United States Patent Office

Des. 197,193
Patented Dec. 24, 1963

197,193

BOTTLE

Sheldon Marks, Encino, Calif., assignor to Jules Berman & Associates, Inc., Beverly Hills, Calif., a corporation of California

Filed June 12, 1963, Ser. No. 75,328

Term of patent 14 years

(Cl. D58—9)

FIG. 1 is a front perspective view of a bottle, showing my new design;

FIG. 2 is a front elevational view thereof on an enlarged scale;

FIG. 3 is a side elevational view thereof taken from the right of FIG. 2;

FIG. 4 is a rear elevational view thereof;

FIG. 5 is a top plan view thereof.

I claim:

The ornamental design for a bottle, substantially as shown.
